APPARATUS FOR POSITIONING COMPONENTS
 Edward H. Craver, Winston-Salem, N.C., assignor to
 Western Electric Company, Incorporated, a corporation of New York
 Filed Aug. 29, 1961, Ser. No. 136,396
 7 Claims. (Cl. 29—271)

This invention relates to apparatus for positioning components and more particularly to a device for positioning components in the center of an enclosure.

In the assembly of components it is often necessary to accurately position certain components relative to each other. It is especially important in the assembly of a rod-like component within a tube or waveguide to precisely center the component between two opposing walls of the waveguide.

An object of this invention is to provide a new and improved device for positioning a component relative to another component for assembly.

Another object of this invention is to provide a mobile device for accurately centering an electrical component between two opposing walls of a waveguide.

An additional object of this invention resides in a carriage for positioning clamping facilities in the center of an enclosure and apparatus for actuating the clamping facilities to hold a component centered in the enclosure.

A further object of this invention is the provision of opposed pairs of crossed links for centering a clamp device between opposed walls of an enclosure wherein control handles are provided for positioning the crossed links in the enclosure and for operating the clamp device.

Still another object of this invention resides in a carriage having wheels mounted to the extremities of opposed pairs of crossed links wherein resilient facilities urge the wheels into engagement with the walls of an enclosure for centering a clamped component between the walls.

A still further object of this invention resides in the provision of a carriage for supporting a clamp in the center of a waveguide and a resilient mechanism for actuating the clamp to hold an electrical component centered in the waveguide.

With these and other objects in view, the present invention contemplates a centering device having pivotally supported pairs of crossed links together with facilities for holding a component against the joint formed by the intersecting crossed links. Wheels rotatably mounted on the ends of the links are urged by spring mechanisms into engagement with opposite walls of a tube so that the midpoints of the links are centered between the walls. A clamp interposed between the pairs of links at the midpoints is also centered between the walls. Control handles, connected to the crossed links and to the clamp, are manipulated for moving the wheels into engagement with the walls and for operating the clamp to hold a component centered between the walls of the tube.

A complete understanding of this invention may be had by referring to the following detailed description and the accompanying drawings illustrating a preferred embodiment thereof, in which:

FIG. 1 is a side elevational view of a carriage for supporting a component clamp between opposed walls of a tube and a control mechanism for actuating the clamp according to the principles of the invention;

FIG. 2 is a cross sectional plan view taken on line 2—2 of FIG. 1 showing two pairs of opposed crossed links provided with wheels for movably supporting the carriage;

2

FIG. 3 is a sectional view taken on line 3—3 of FIG. 1 showing a clamp frame supported by the crossed links for positioning arms of the clamp at a predetermined distance from the walls of the tube;

FIG. 4 is a sectional view taken on line 4—4 of FIG. 1 showing a carriage frame for pivotally supporting the crossed links; and

FIG. 5 is a sectional view taken on line 5—5 of FIG. 1 showing a trailer frame supported on wheels for movement relative to the carriage frame shown in FIG. 4 for actuating the arms of the clamp.

Referring in general to FIG. 1, a carriage 15 is shown provided with two pairs of links 16 pivotally mounted on a first H-shaped or carriage frame 17. The links 16 cross at their midpoints and rotate on pivot pins 18 provided on a second H-shaped or clamp frame 19. When the carriage 15 is inserted into the open end of a hollow enclosure or tube such as a waveguide 21, compression springs 22 are effective to urge two sets of wheels 23 and 24 mounted on the crossed links 16 outwardly into engagement with the opposite walls 26 and 27 of the tube 21 so that the pivot pins 18 of the crossed links 16 and the clamp frame 19 are positioned in the center of the tube 21. Crescent-shaped arms 28 and 29 of a clamp 30 are pivotally mounted on the clamp frame 19 and are thereby centered with respect to the walls 26 and 27 of the tube 21 for holding a component 31. Control handles, generally referred to by the reference numeral 32, are manipulated to adjust a trailer 33 axially in the tube 21 relative to the carriage 15 for moving the arms 28 and 29 of the clamp 30. Jaw portions 35 of the arms 28 and 29 hold the component 31 against the crossed links 16 so that the component 31 is positioned equidistantly from the opposite walls 26 and 27 of the tube 21.

Carriage

Referring in detail to FIGS. 1 and 4, the carriage 15 is shown including the carriage frame 17 which is provided with slots 37 for receiving axles 38 between the extremities of opposed arms 39 of the frame 17. The axles 38 rotatably support one end of the links 16 and also support the wheels 23 and 24 which are received in slots 47 formed in the same end links.

A cutout portion 48 is formed at the midpoint of each link 16 (FIGS. 1 and 4). An aperture centered between the walls of the cutout portion 48 is formed through the links 16 for receiving the pivot pins 18 that are threaded into a cross-bar portion 49 of the clamp frame 19 (FIG. 3).

Axes 50 are also interposed between the free ends 53 of the crossed links 16. Four wheels 23 and 24 are mounted for rotation on the axes 50 and are received in slots 51 provided in the free ends 53 of the crossed links 16 (FIG. 3).

Aligned apertures 54 (FIG. 2) are formed in each of the axles 38 and 50 for receiving rods 56 and 57 as shown in FIG. 1. A block 58 is fastened to one end of each of the rods 56 and 57 for limiting the movement of the rods to the right through the axle 50. Nuts 59 are threaded on the other end of the rods 56 and 57. A second block 60, slidably mounted on each of the rods 56 and 57 between the axle 38 and the nuts 59, is urged against the axle 38 by the compression spring 22. It may be appreciated that upon insertion of the carriage 15 into a tube 21, the compression springs 22 are effective to urge the axles 38 and 50 toward each other so that the upper and lower sets of wheels 23 and 24 are respectively urged outwardly into engagement with the upper and lower walls 26 and 27 of the tube. Inasmuch as the pivot pins 18 pass through the pairs of crossed links 16 at a point that is

equidistant from the ends of the links, the pivot pins 18 are thus positioned in the center of the tube 21.

Clamp

Referring to FIGS. 1 and 3, it is apparent that the clamp frame 19 is supported by the pivot pins 18 in the center of the tube 21. Shafts 62 and 63 are received in opposed apertures formed through the extending arms 64 of the clamp frame. The crescent-shaped clamping arms 28 and 29 are pivotally mounted on the respective shafts 62 and 63 at a point intermediate their ends. An arm operating link 65 is pivotally connected to one end of each of the arms for rotating the arms on the shafts into the position shown in FIG. 1 wherein a component 31 is engaged and urged by the jaw portions 35 of the arms into engagement with the crossed links 16. It may be appreciated that the component 31 is thereby held by the jaw portions 35 in the position shown in FIG. 1 in horizontal alignment with the joint of the cross links 16 and is thus centered between the walls 26 and 27 of the tube 21.

Trailer

A clamp-operating device or trailer 33 is connected to the operating links 65 for moving the links relative to the clamp frame 19 to pivot the arms 28 and 29. Referring to FIG. 5, the trailer 33 includes a third H-shaped or trailer frame 67 that is provided with axles 68 received in apertures formed in the extremities of the arms 69 on the third frame. A wheel 70 is mounted between the arms 69 on each of the axles 68 to permit the trailer 33 to be rolled or advanced into the tube 21. As shown in FIG. 5, the axles 68 are received in bores 72 formed in the trailer frame so that the wheels 70 are free only to rotate.

With this construction, it is contemplated that successive waveguides will have approximately the same dimensions. However, where the dimensions of successive waveguides are substantially different, the present centering apparatus can be modified by spring loading and slidably mounting the wheels 70 so that the wheels are urged outwardly into engagement with the opposite walls of the tube 21.

Control handles

Control handles 32 are provided for enabling an operator to insert the carriage 15 and trailer 33 into a tube or waveguide and to operate the clamp 30. Referring to FIG. 1, a first control handle 74 includes a solid rod 75 that is slidably mounted in a first control sleeve 71 which is in turn slidably received in a second control sleeve 86. A neck or reduced diameter portion 79 of the rod 75 is forced into and thus frictionally secured in an aperture formed in the clamp frame 19. The first control sleeve 71 is provided with a knurled handle portion 80. The sleeve 71 is slidably mounted over the first control handle 74 and is held in an aperture 77 formed in the carriage frame 17 by a pin 81 (as shown in FIG. 1). A compression spring 82 is mounted about the outer periphery of the first sleeve 71 between the carriage and trailer frames for urging the carriage frame 17 against a collar 84 that may be adjustably fixed to the first control rod 75 (FIG. 1). When the carriage frame 17 is urged against the collar 84 by the spring 82, the trailer 33 is urged to the right (as viewed in FIG. 1), whereby the clamp-operating links 65 urge the clamping arms 28 and 29 into the clamping position for holding the component 31 against the crossed links 16 as shown in FIG. 1. Thus the clamping arms 28 and 29 are automatically urged into clamping position by the compression spring 82.

A third control handle 85 is provided for manually adjusting the position of the jaws. The third control handle 85 includes the second control sleeve 86 that is slidably mounted on the first control sleeve 71 and which is received in an aperture 76 provided in the trailer frame 67. By holding the first and second handles 74 and 80

stationary, the third handle 85 may be advanced axially for moving the trailer 33 to open and close the jaw portions 35 of the clamp arms 28 and 29.

It may be appreciated that if the operator holds the first control handle 74 at a fixed position to thus hold the second frame 19 at a fixed position, the second control handle 80 may be moved axially for advancing the carriage frame 17 relative to the clamp frame 19. The sets of wheels 23 and 24 on the crossed links 16 may thus be moved toward or away from the walls 26 and 27 of the tube 21 depending upon the direction of movement of the second control handle 80.

Assuming that the operator desires to insert and center a component 31 in the tube 21, the operation of the centering device is as follows. The operator places the carriage 15 and trailer 33 on a suitable support such as a table (not shown). The operator then holds the first control handle 74 at a fixed position. The third control handle 85 is then moved axially away from the first control handle for pivoting and opening the jaws 35 of clamping arms 28 and 29. The component 31 to be centered is then placed against the crossed links 16 (as shown in FIG. 1) and the third control handle 85 is released. The action of the compression spring 82 urges the trailer 33 toward the right (as viewed in FIG. 1) away from the carriage frame 17, so that the jaws 35 return to the clamping position and hold the component 31 against the crossed links 16. The operator then grasps the second control handle 80 and advances it axially along the first handle 74. The carriage frame 17 is thereby advanced away from the clamp frame 19, whereby the upper and lower sets of wheels 23 and 24 of the carriage 15 move inwardly toward each other so that the sets of wheels are spaced apart less than the distance between the walls 26 and 27 of the tube 21. While holding the control handles 32 in this position, the operator then inserts the centering device in the tube 21. The operator then releases the second control handle 80 so that the upper and lower sets of wheels 23 and 24 are urged outwardly into engagement with the opposite walls 26 and 27 of the tube 21 by the action of the compression springs 22. As above described, the clamp frame 19, and thus the clamping arms 28 and 29 and the component 31 to be centered, are thereby positioned in the center of the tube 21.

If the component 31 is then permanently attached to the tube, the operator can release the component by manipulating the handles, and more particularly, the operator holds the first control handle 74 at a fixed position and advances the third control handle 85 away from the first control handle 74 against the action of the compression spring 82. The clamping arms 28 and 29 are thereby moved into an open position for releasing the component 31 whereupon the carriage 15 and trailer 33 may be removed from the tube 21.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. In a device for positioning an element within an enclosure, a plurality of pairs of crossed links positionable within said enclosure, a common pivot pin passing through each pair of crossed links at the intersections to form common pivot joints, means for urging said links to pivot about said common pivot pin to move the extremities of said links into engagement with said enclosure, an arm having a jaw for holding the component against the common pivot joints, means for pivotally mounting said arm, and means for urging said arm to pivot said jaw toward said common pivot joints.

2. In a device for positioning a component between opposed surfaces, a clamp frame, carriage means for lo-

cating the clamp frame between said opposed surfaces, clamp means having opposed jaws pivotally mounted on said clamp frame for holding a component, trailer means supported on said opposed surfaces, means pivotally interconnecting said clamp means and trailer means for imparting movement of said trailer means to said clamp means, and means interposed between the carriage means and the trailer means for urging the trailer means away from the carriage means to pivot the opposed jaws into engagement with a component.

3. In a device for centering a component between opposite walls of an enclosure, a clamp frame, pairs of crossed links pivotally mounted to said clamp frame at a point equidistant from the ends of the links, a carriage frame pivotally connected to one end of each link for supporting said ends, roller means mounted for rotation on the opposite ends of said links for engaging the opposite walls, means for urging the pairs of links on said clamp frame to move the roller means against the opposite walls, and clamp means mounted on said clamp frame for holding a component against the pivot joint formed by said crossed links.

4. In a device for centering a component between opposed walls of a tube, a carriage including two pairs of pivotally mounted crossed links having wheels mounted for rotation on the ends of the links, a frame interposed between the two pairs of crossed links at the pivot points of the links, means provided on the carriage for urging the crossed links to rotate the wheels into engagement with the walls of the tube, clamp means mounted on the frame for holding a component against the pivot points, means mounted for axial rolling movement in the tube relative to the frame for operating the clamp means, and means interposed between said carriage and the operating means for rolling the clamp operating means axially in the tube away from the carriage to close the clamp means.

5. In a device for centering a component between opposite walls of an enclosure, a clamp frame, pairs of links crossed and pivotally mounted to the clamp frame at a point equidistant from the ends of the links, a carriage frame pivotally connected to one end of each link that extends in a common direction from said point for supporting said ends, roller means mounted for rotation on the ends of said links for engaging said opposite walls, a first control means fixed to the clamp frame for moving the clamp frame within the enclosure, second control means fixed to the carriage frame for moving the carriage frame relative to the clamp frame to pivot the links to move the roller means into engagement with the walls, a clamp having a pair of jaws pivotally mounted on said clamp frame for holding a component against

the intersections of said crossed link centered between said opposite walls, and third control means connected to said jaws for urging the jaws into engagement with the component.

5 6. In a device for centering a component between opposed surfaces, two pairs of links crossed at the mid-point of the links, a clamp frame, means for pivotally supporting the pairs of links at the midpoints, on said clamp frame, a carriage frame pivotally connected to one 10 end of each link that extends in a common direction from said midpoint, axles supported by the extremities of the links, said axles extending between the extremities of the links of one pair and the corresponding extremities of the links of the other pair, wheels rotatably mounted on 15 the axles, resilient means connected between pairs of axles for urging the axles together to pivot the links and advance the wheels outwardly into engagement with the opposed surfaces, a pair of crescent-shaped clamping jaws pivotally mounted to said clamp frame for holding 20 a component against the intersections of said pairs of crossed links to center the component between said surfaces, operating means connected to the jaws for pivoting said jaws on said clamp frame, and resilient means interposed between the operating means and the 25 carriage frame for rendering the operating means effective to pivot the jaws into position to hold the component.

7. A device for positioning a component in an enclosure having opposed walls comprising 30 spaced pairs of crossed links positionable within said enclosure and pivotally mounted at the centers thereof, clamp means movable into and out of engagement with the component for holding the component against the pivot joint formed by said crossed links, first means for urging the extremities of the links away from the opposed walls of said enclosure, second means for moving the clamp means out of holding engagement with the component, and 35 means rendered effective upon the release of said first and second means for urging the extremities of said crossed links into engagement with the opposed walls of said enclosure and for moving the clamp means into engagement with the component.
